(57) **CLAIM**

The ornamental design for stowable jacket, as shown and described.

DESCRIPTION

FIG. 1 is a left front perspective view of the stowable jacket embodying the new design;

FIG. 2 is a left side elevational view thereof;

FIG. 3 is a front elevational view thereof;

FIG. 4 is a rear elevational view thereof;

FIG. 5 is a top plan view thereof; and,

FIG. 6 is a bottom plan view thereof.

FIGS. 1-6 show features of the stowable jacket in broken lines. These features are shown for environmental purposes and do not form any part of the claimed design.
